ROBERT H. L. JANNEY, OF CHICAGO, ILLINOIS; GARDNER L. BOOTH, EXECUTOR OF,
SAID ROBERT H. L. JANNEY, DECEASED, ASSIGNEE TO MANNIE HAMILTON JANNEY.

TRANSITIONAL COUPLER MACHINERY.

Application filed July 2, 1928. Serial No. 578,686.

This invention relates to transitional coupler mechanism.

As is well known in certain foreign countries, railway cars are connected to each other by a hook and chain arrangement, adjacent ends of the cars being provided with cooperating bumpers to prevent damage to the car structures proper and to retain the cars a predetermined distance apart to prevent the connection from being disturbed. In some of these foreign countries, the railway companies are changing over from the hook and chain connection between cars to a connection made by automatic couplers. It will be appreciated that all of the cars cannot be equipped with automatic couplers at the same time, but nevertheless, the cars which are equipped with automatic couplers and those which are not so equipped must be connected in the same train. In other words, there is a transitional period in which adjacent cars may be connected by the old hook and chain arrangement, or by an automatic coupler on one car and a hook on an adjacent car connected by a chain or similar element.

Accordingly, one object of my invention is to provide simple, improved and efficient transitional coupling mechanism for cars which may be readily adjusted or substituted in accordance with a transitional condition.

Another object is to provide a transitional coupling arrangement adapted to meet all of the requirements for successful commercial operation.

These and other objects are accomplished by means of the arrangements disclosed on the accompanying sheets of drawings, in which—

Figure 1 is a fragmentary top plan view of a railway car draft mechanism embodying my invention;

Figure 2 is a fragmentary longitudinal sectional view showing the main parts in side elevation;

Figure 3 is a fragmentary end elevation of a car showing a carrier iron adapted to support a hook coupler, the shank of the hook being shown in section;

Figure 4 is a fragmentary top plan view, on a larger scale than that shown in Figure 1, and showing the automatic coupler substituted for the hook coupler;

Figure 5 is a fragmentary side elevation

of the same arrangement, showing the striking casting, the reversible carrier iron and plate in section;

Figure 6 is a fragmentary end elevation of a car similar to that shown in Figure 3 but with the carrier iron reversed for supporting the shank of the standard automatic coupler, which shank is shown in section;

Figure 7 is a fragmentary top plan view, 65 parts being in section, of a modified form of draft mechanism embodying my invention;

Figure 8 is a vertical longitudinal sectional view of the arrangement shown in Figure 7, some of the parts being shown in side elevation;

Figure 9 is a sectional view taken in the plane of line 9—9 of Figure 8;

Figure 10 is a sectional view taken in 75 the plane of line 10—10 of Figure 8;

Figure 11 is a fragmentary plan view of draft mechanism embodying a modified form of my invention and shown applied to draft mechanism including a horizontal 80 draft key;

Figure 12 is a partial vertical longitudinal sectional view of the arrangement shown in Figure 11;

Figure 13 is a fragmentary side elevation 85 of a modification of my invention showing some of the parts in section;

Figure 14 is a fragmentary plan view of the arrangement shown in Figure 13; and

Figure 15 is a detail front view of the 90 striking casting and reversible carrier iron, showing the shank of the coupler hook in section and supported by the carrier iron.

The various novel features of the invention will be apparent from the following 95 description and drawings, and will be particularly pointed out in the appended claims.

Referring first to Figures 1 to 6 inclusive, it will be noted that my invention 100 is disclosed in connection with a railway car having center sills 20 which are connected at their ends by a striking casting 21, there being draft gear means 22 of the frictional type, mounted between said 105 center sills. The draft mechanism includes a vertical yoke 23 having spaced arms 24, the front ends of which are preferably connected by tie straps 25. Extending between the front ends of the yokes 24 and 110

through aligned vertical openings 26 therein is a vertical draft key 27 which is supported in its operative position by a cross pin 28 in turn supported by lugs 29 depending from the lower yoke arm 24.

Referring now particularly to Figures 1 to 3 inclusive, it will be noted that the right hand car shown in Figure 2 is provided with an old style hook 30 and the left hand car 10 is provided with a modified hook 31, which hooks are connected by any suitable connecting means 32 for connecting the adjacent ends of adjacent cars.

Attention is called particularly to the hook arrangement associated with the left hand car in which the shank 33 of hook 31 extends rearwardly and is provided with an integrally formed loop 34, preferably welded, through which the vertical draft key 27 extends. It will be appreciated that unless some special means is provided for centralizing the loop portion 34 of the hook on the draft key 27 that such loop portion would probably fall below its center position, it being understood that the yoke 23 here shown, is a standard yoke for standard automatic couplers in which the yoke arms 24 are spaced apart the regular standard distance for receiving the shank of a standard automatic coupler. To properly centralize the loop portion 34 of the coupler hook 31 there is provided, as shown particularly in Figure 2, a plurality of shims or spacing blocks 35. In this same connection it is necessary to properly support the front end of the coupler hook 31 for giving it the proper centralized position. To this end a reversible carrier iron 36 is supported by a bolt 37 which connects depending lugs 38 on the carrier iron 21. As shown in Figures 1, 2 and 3, and particularly the latter, the reversible carrier iron 36 is arranged with its spaced legs 39 in an upward position, so that the receiving pocket 40 between the legs 39 is open upwardly to receive and retain the shank 33 of the hook 31 in a central position.

Referring particularly to Figure 6, it will be noted that an uncoupling rod 41 is provided and has one end supported by a bracket 42 connected to an end portion of the car and also supported by an open link 43 forming the lower part of a chain supported at its upper end by the bolt 37.

Let it be assumed now that it is desired to change over from the transitional coupling mechanism shown in Figures 1, 2 and 3, to the automatic coupler mechanism, as shown in Figures 4, 5 and 6. To accomplish this result, it is merely necessary to withdraw the key supporting pin 28 to permit the vertical draft key 27 to drop and to withdraw the bolt 37 for withdrawing the coupler hook 31. The reversible carrier iron 36 is then reversed in position from that

shown in Figure 3 to that shown in Figure 6, and secured in such position by the bolt 37, whereupon the automatic coupler 44 may be set in position and supported by the carrier iron 36 and the opening 45 in the rear 70 of the shank 46 of the coupler alined with the openings 26 in the yoke arms 24 for the passage of the draft key 27. The pin 28 may then be set in position for supporting the key 27 and the uncoupling rod passed 75 through the eye 47 of the lock lifter 48 of the automatic coupler 44. The changing over from the hook coupler to the automatic coupler requires a minimum amount of time and the shifting of a minimum number of 80 parts.

In Figures 7 to 10 inclusive, substantially the same arrangement is shown, but in connection with a different form of draft gear, including twin draft gear springs 49, which arrangement has its advantages for equipment of the weight required on some foreign cars, the arrangement shown in Figures 7 to 10 inclusive, being lighter and cheaper and possibly a more suitable construction for 85 foreign cars as now built. There is another difference shown in Figures 7 to 10 inclusive, in that the vertical draft key 27 is supported by a cross tie strap 50 instead of a pin 28, as shown in Figures 1 to 6 inclusive. Also in Figures 7 to 10 inclusive, a modified form 90 of spacer block 51 is provided, the function of such block, however, being the same as in the case of the spacer blocks shown in Figures 1 to 6 inclusive, that is, to support and centralize the loop 34 of the coupler hook 31.

In Figures 11 and 12 there is shown a modified arrangement in which a horizontal draft key 52 is provided which connects the side members 53 of a yoke. In this instance the rear loop portion 54 of the coupler hook 55 is centrally located by spacers 56 mounted at either side of the loop 54 on the draft pin 52. The reversible carrier iron 36 supporting the front end of the coupler hook 55 is the same as that shown in Figures 1 to 10 of the drawings.

In Figures 13, 14 and 15 there is shown another modification of the arrangement disclosed in Figures 1 to 3 inclusive, of the drawings, in which instead of providing the shank 57 of the coupler hook 58 with a loop portion which receives the vertical draft key 59, it is threaded through a hollow block 60 and secured thereto by a nut 61, which block has vertical aligned openings 62 through which the vertical draft key 59 extends. The forward end of the shank 57 of the coupler hook 58 is supported in a reversible carrier iron 63.

By means of the various transitional coupler mechanisms herein disclosed, it is a relatively simple matter to change to the 125 standard automatic coupler system.

It is my intention to cover all modifications of the invention falling within the spirit and scope of the following claims.

I claim:

1. In transitional coupler mechanism, the combination of a yoke having spaced walls between which the shank of a standard automatic coupler is adapted to be received, a key extending between the walls of said yoke, a hook coupler directly connected to said key, and separate means for centering said hook with respect to said key.

2. In transitional coupler mechanism, the combination of a yoke having spaced walls between which the shank of a standard automatic coupler is adapted to be received, a key extending between the walls of said yoke, a hook coupler directly connected to said key, and spacing means associated with said key for centering said hook with respect thereto.

3. In transitional coupler mechanism, the combination of a yoke having spaced walls between which the shank of a standard automatic coupler is adapted to be received, a key extending between the walls of said yoke, a hook coupler operatively connected to said key, and a carrier iron adapted to support and position selectively a standard automatic coupler or said hook coupler, depending upon which one is in use.

4. In transitional coupler mechanism, the combination of a yoke having spaced walls between which the shank of a standard automatic coupler is adapted to be received, a key extending between the walls of said yoke, a hook coupler operatively connected to said key, means for centering said hook with respect to said key, and a carrier iron having selective supporting portions, adapt-

ed to position and support selectively a standard automatic coupler or said hook coupler, depending upon which one is in use.

5. In transitional coupler mechanism, the combination of a yoke having spaced walls between which the shank of an automatic coupler is adapted to be received, a key extending between the walls of said yoke, a hook coupler operatively connected to said key, means associated with said key for centering the rear of the hook coupler with respect to said key, and a reversible carrier iron having different supporting portions whereby said iron in one position is adapted to support and center the front end of said hook coupler and in another position is adapted to support and center a standard automatic coupler.

6. In transitional coupler mechanism, draft means to which either a standard automatic coupler or a hook coupler may be operatively connected, and an adjustable carrier iron having selective supporting and positioning means which in one position is adapted to support and center a hook coupler and in another position is adapted to support and center a standard automatic coupler.

7. In transitional coupler mechanism, draft means to which either a standard automatic coupler or a hook coupler may be operatively connected, and a carrier iron having selective supporting and positioning means which in different positions is adapted to support and center a standard automatic coupler or a hook coupler.

Signed at Chicago, Illinois, this 3rd day of July, 1922.

ROBERT E. L. JANNEY.
